PAGE 2

Fig. 2

Fig. 3FIGS. 1 and 2 illustrate a plan view of a plastic sheet material showing my new design which is repeated in the vertical directions to extend above and below FIGS. 1 and 2, and which terminates at the left-hand edge of FIG. 1 and the right-hand edge of FIG. 2; the overall width of the design being the combined widths of FIGS. 1 and 2.

FIG. 3 is an enlarged plan view of a portion of my new design taken within the confines of the dotted lines of FIG. 1.

I claim:

The ornamental design for a plastic sheet material, substantially as shown.
